United States Patent Office.

H. C. MOORE, OF SPRINGFIELD, MASSACHUSETTS, ASSIGNOR TO HIMSELF
AND CHARLES ROBINSON, OF THE SAME PLACE.

Letters Patent No. 65,685, dated June 11, 1867.

IMPROVEMENT IN SKATES.

The Schedule referred to in these Letters Patent and making part of the same.

TO ALL WHOM IT MAY CONCERN:

Be it known that I, H. C. Moore, of Springfield, in the county of Hampden, and State of Massachusetts, have invented an Improved Skate; and I do hereby declare that the following is a full and exact description thereof, reference being had to the accompanying drawings making part of this specification—

Figure 1 being a top view of the skate.

Figure 2, a bottom view thereof.

Figure 3, a side view of the same.

Like letters designate corresponding parts in all of the figures.

The toe-plate A and heel-plate D of the skate are separate, and at some distance from each other, and they are respectively attached to the two ends of the runner B. The runner is more or less elastic, and thus it is allowed to bend or yield in the middle, giving elasticity and separate movement to the toes and heel of the foot. The toe-clamps C C have flanches c c, which extend transversely under the toe-plate A, and are guided and limited in movement by slots i i in the flanches c c, and studs or screws b b passing through said slots into the toe-plate, substantially as represented. The clamps are adjusted out and in to suit the size of the boot or shoe, by means of hook or saw-teeth notches l l, in the adjacent edges of the flanches c c, hooking into each other as represented, and holding one another in place. A thumb-screw, s, fig. 3, passing up through the supporting part a of the runner, by the side of one of the flanches c c, keeps the teeth interlocked. When the teeth are to be changed to adjust the clamps, the screw is turned out till the flanches are free to separate. Then when they are intermatched again in the desired position, the screw s is again turned in, and locks them together. The other edge of the two lapping flanches abuts against the side of the notch or mortise of the runner in which they slide. This adjustment of the toe-clamps can be done at home, before going on the ice, and, once adjusted to a pair of boots or shoes, need not be changed till they are required to be adjusted to other boots or shoes. The skate is fastened to the boot or shoe at the heel, there being a heel-clamp E at the rear end of the skate to fit the rear end of the boot or shoe heel. This heel-clamp is adjusted forward or backward, to suit the length of boot or shoe, by means of hook-teeth f f on the edges of its flanch e, fitting into corresponding notches in the heel-plate D, substantially as shown. The adjustment is effected by raising the flanch e above the heel-plate, and shifting the teeth and notches as desired. The flanch is secured in place by a screw-bolt, g, which passes down through a longitudinal slot therein, and through a hole in the heel-plate and upper part of the runner. It is held in place by a nut, t, screwing upon it below the said heel-plate and part of the runner. To allow the flanch of the heel-clamp to be raised, for shifting positions, the nut t is unscrewed till the shifting can be effected, and then it is tightened again on the screw. The skate is fastened to the heel of the boot or shoe by means of a cam or eccentric, G, located just in front of the boot or shoe heel, and turning in bearings d d which project upward from the heel-plate D. This eccentric has a handle, p, attached to it, by which to work it, and preferably has cross-notches, or equivalent roughened surface m, on the bearing side, to enable it to hold more securely. To fasten the skate, the handle p is turned up toward the position shown by red lines in fig. 3, far enough to allow the heel of the boot or shoe to be inserted between the cam G and heel-clamp E. The handle p is then turned toward the position shown by black lines in fig. 3, thereby causing the eccentric to wedge itself against the boot or shoe heel till it holds the skate with sufficient force and security. Any tendency of the boot or shoe heel to work out only causes the eccentric to wedge more tightly. When the skate is to be taken off, the handle p is raised again, and the skate is at once released. This means of attaching the skate is simple, secure, and firm; and yet is very convenient, and leaves the foot free and uncramped in the boot or shoe.

What I claim as my invention, and desire to secure by Letters Patent, is—

The hook-notches l l, in the adjacent edges of the flanches of the toe-clamps, in combination with the thumb-screw s, which holds the flanches together, substantially as and for the purpose specified.

I also claim the combination of the hook-notches f f, in the edges of the flanch of the heel-clamp, the corresponding notched opening in the heel-plate D, the bolt g, and nut t, substantially as and for the purpose herein specified.

I also claim the notched eccentric G, with its handle p, turning up and down under the foot, and arranged so that it tightens more securely as the heel tends to work out, substantially as herein specified.

The above specification of my improved skate signed by me this fifteenth day of February, 1867.

H. C. MOORE.
